CARBURETOR

Scott F. Hunt, South Bend, Ind., assignor to
 Bendix Products Corporation, South Bend, Ind.,
 a corporation of Indiana

Application September 17, 1934, Serial No. 744,329

22 Claims. (Cl. 123—119)

This invention relates to carburetors, and more particularly to means for controlling the choke valve of carburetors, so as to furnish the most economical and efficient combustible mixture to the engine.

The richness of the mixture supplied by the carburetor is usually controlled by varying the quantity of air admitted to the carburetor, by means of a choke valve which operates to vary the effective area of the air inlet passage.

It is desirable to control the choke valve automatically, in such a manner that the carburetor will supply a rich mixture when the engine is cold, and a progressively leaner mixture as the engine warms up to normal operating temperature.

This invention is an improvement upon the device disclosed in Patent 2,071,633, issued February 23, 1937, to the present applicant, and in its preferred form covers an automatic choke mechanism constituting an improvement on that disclosed in Patent No. 1,945,191, issued January 30, 1934, to the present applicant. The device hereinafter disclosed includes a carburetor having an unbalanced choke valve, urged toward its open position by the force of the air entering the air inlet passage and impinging on the unequal areas of the valve on either side of the choke shaft. The force of gravity acting on the unbalanced choke valve also tends to open the valve.

The choke valve is yieldingly urged toward the closed position by a thermostatic element which exerts on the choke valve a force which is dependent upon the temperature of the thermostat. When the engine begins to operate under its own power, an electric current is passed through a resistance coil, placed in juxtaposition to the thermostat. The thermostat becomes heated by the coil and exerts a decreasing force urging the choke valve toward closed position.

The resistance coil placed in juxtaposition to the thermostat is controlled by the engine ignition switch, and by a switch automatically closed only during engine operation.

An object of this invention, is, therefore, to provide an improved means for controlling the choke valve of a carburetor in accordance with engine operating conditions.

Another object is to provide simple means for heating a thermostatic element, operably connected with a choke valve.

A still further object of the invention is to provide electric means for heating the thermostat operable only upon engine starting.

Another object of the invention is to provide

a compact and serviceable unit of the class described, which will be less susceptible to maladjustment and failure in service, and economical to manufacture.

5 Other objects and advantages of the invention will be apparent from the following description, taken in connection with the accompanying drawings, submitted for purposes of illustration only, and not intended to define the scope of the invention, reference being had for that purpose to the subjoined claims.

In the drawings, wherein similar reference numerals refer to similar parts throughout the several views:

15 Figure 1 is a longitudinal view, partly in section of a carburetor equipped with a device of the present invention;

Figure 2 is a view taken on the line 2—2 of Figure 1, looking in the direction of the arrows;

20 Figure 3 is a view taken on the line 3—3 of Figure 1, looking in the direction of the arrows;

Figure 4 is a diagrammatic view showing the electric circuits of the device;

Figure 5 is a view, partly in section, showing 25 one type of automatic switch operating mechanism;

Figure 6 is a sectional view of a modified form of switch operating mechanism wherein engine exhaust pressure is employed to close the circuit;

Figure 7 is a sectional view of a further modification, showing a thermostatically operated switch;

Figure 8 is a sectional view of a further modification wherein manifold vacuum is employed to actuate an electric switch; and

Figure 9 is a diagrammatic view of a further modification disclosing an electrically operated relay.

40 Referring more particularly to Figure 1, there is shown for purposes of illustration, a downdraft, plain tube carburetor, having an air inlet passage 10 communicating with a main carbureting passage 12. The air inlet passage 10 is adjustably controlled by an unbalanced choke valve 14, fixed to a choke shaft 16. The choke valve 14 is provided with a spring pressed poppet relief valve 18, to permit a small amount of air to bypass the choke valve under certain operating conditions.

The main carbureting passage 12 is fitted with a secondary venturi 20, into the most restricted section of which a primary venturi 22 discharges. The primary venturi is supported by a fin (not shown) extending from the walls of the main

carbureting passage. A main fuel discharge nozzle 24 is positioned in the most restricted section of the primary venturi 22, and receives fuel from the conventional fuel reservoir 26, through a fuel duct extending through the fin supporting the primary venturi 22.

The flow of combustible mixture, formed by the fuel discharged from the fuel nozzle 24, and the air entering the air inlet passage 10, is controlled by a throttle valve 28, fixed to a throttle shaft 30. When the throttle valve 28 is closed, fuel for idling purposes is furnished from the fuel reservoir 26, by a duct 32 terminating in an idling nozzle 34, posterior to the throttle valve 28. Air for idling purposes is supplied through a passage 36, anterior to the throttle valve 28, and communicating with the passage 34. An idling adjustment screw 38 is provided, by which the quantity of combustible mixture bypassing the throttle valve 28 may be adjustably controlled.

The choke valve 14 is actuated in the closing direction by a thermostatic element 40, housed within a chamber 42, formed by a flat plate 44 and a metal casing 46. The chamber 42 may be heat-insulated in any suitable manner, if desired. The choke shaft 16 projects through the plate 44 and is fixed to the inner end of a spiral thermostat 40 in such a manner as to be insulated therefrom, as shown, and actuated thereby. The metal casing 46 is provided with an insulated terminal 48, to receive one end of an electric wire 61. An electric resistance coil 52 is fixed on the inside of the casing 46 in heat exchange relation to the thermostat 40 and is separated from the casing 46 by an insulating member 47. A snap contact member 54 is connected with one end of the resistance coil 52, and bears against the inner end of the thermostat 40 in electrical conducting relation. The outer end of the thermostat 40 is formed in the shape of a hook, to engage a stop member 56, fixed in the plate 44 so as to form an electrical connection or ground circuit therewith.

As described hereinafter, the thermostat 40 is heated electrically when the engine begins to operate on its own power, and the circuit is broken when the thermostat becomes heated and uncoils, thereby moving the hooked end out of contact with the stop member 56, to break the electric circuit through the resistance coil 52.

Figure 4 illustrates the relation of the electric circuits of the device to those of an internal combustion engine. Electric current is supplied by a storage battery represented at 58, through the wires 60, 61 and 62 when an ignition switch 63, interposed in the wire 61, is closed, to the ignition circuit 59. When the ignition switch 63 is closed and the engine is started, an engine-operated auxiliary switch, having a movable contact member 64, and a fixed contact member 65, is closed by automatic switch operating mechanism 66 described hereinafter, whereupon an electric current flows through the wire 67 to the resistance coil 52, to heat the chamber 42 and the thermostat 40. As the thermostat 40 becomes heated, it will tend to uncoil, thereby exerting a decreasing force tending to close the choke valve 14, and finally uncoiling to such an extent that the hooked end disengages the stop member 56, thereby breaking the electric circuit and discontinuing the flow of current through the resistance coil 52.

When the engine is operating below a predetermined speed, the current passing through the resistance coil 52 is supplied by the battery 58,

but when the speed of the engine increases, an engine-operated generator 68 supplies the current. The generated current is passed through a lead 69 to a solenoid 70 comprising a resistance coil 71 wound upon a core 72. When the voltage of the generated current is greater than that supplied by the battery 58, the solenoid 70 will become energized and draw an arm 73 toward the core 72, whereupon a movable contact point 75 is moved into engagement with a fixed contact point 77, in the known manner. The generator 68 then furnishes the current for the ignition circuit and the resistance coil 52, through a wire 78 connected to the fixed contact point 77 and the wire 61. Any excess current supplied by the generator 68 is passed through the battery 58 as a charging current in the usual manner. When the voltage of the generated current is less than that supplied by the battery 58, as when the engine is stopped, the solenoid 70 becomes deenergized, whereupon a spring 77 moves the arm 73 to the right as viewed in Figure 4, to move the contact point 75 away from the fixed contact 77 to interrupt the current flowing from the generator 68.

Since it is desirable that the heating of the thermostat be effected proportionately to the heating of the engine, the flow of current through the resistance coil 52 is started only when the engine is actually running, and not merely when the ignition switch is turned on. If the heating of the resistance coil began immediately upon turning the ignition switch, the thermostat 40 might permit the choke valve 14 to open before the engine had started, if it failed to start promptly, or if the operator failed to actuate the starting mechanism (not shown) promptly upon turning the ignition switch.

To obviate this difficulty the present invention incorporates an auxiliary switch having movable and fixed contact members 64 and 65 respectively, operable automatically upon engine starting, by a switch operating mechanism 66.

Figure 5 illustrates one type of switch operating mechanism 66 wherein oil pressure developed by a conventional oil pump represented at 74, is employed to actuate a piston 76, in a cylinder 78, to move a lever 80 operably connected to the piston 76 by a rod 82. The lever 80 carries the movable contact point 64, which engages the fixed contact point 65 when the piston 76 is actuated, thereby closing an electric circuit through the resistance coil 52. When the oil pressure drops below a predetermined value, as when the engine is stopped, a spring 88 returns the piston 76 to its inoperative position, wherein the contact points 64 and 65 are separated.

Figure 6 shows an arrangement wherein exhaust pressure is employed to close the heating circuit. An unbalanced valve 90 is mounted in the exhaust pipe 92. When the engine is operating, the pressure of the exhaust gases rotates the valve 90 in the counterclockwise direction, thereby rotating an arm 94, fixed thereto, to exert tension on a link 96, operably connected to a crank 98 to move the contact points 64 and 65 together to close the heating circuit. When the engine is stopped, a spring 102 separates the contact points 64 and 65 to break the circuit.

Figure 7 illustrates a device in which a thermostatic element 104, carrying the movable contact member 64, is enclosed by a casing member 106, and is subjected to the heat of the exhaust gases in the manifold 108 through an aperture 109 in the walls thereof. When the engine has

started, the thermostatic element 104, subjected to the heat of the exhaust gases, becomes deformed, and moves to the position indicated in dotted lines, whereby the movable contact member 64 engages the fixed contact member 65 to close the circuit through the resistance coil 52 of Figure 4. When the engine has stopped and cools down, the thermostatic element 104 returns to its original position to separate the contact points 64 and 65 to break the circuit through the resistance coil 52.

Figure 8 illustrates an embodiment wherein the vacuum developed in the engine manifold 111 is applied through a pipe 110 to one end of a cylinder 112. When the engine is operating, the pumping action of the engine (not shown), is exerted in the cylinder 112 to move a piston 114 to the left, thereby compressing a spring 116. The piston rod 118 and the connection 120 move the contact point 64 into engagement with the contact point 65 to close the circuit and heat the thermostat 40. When the engine is stopped, the spring 116 moves the contact point 64 away from the fixed point 65 to break the circuit through the resistance coil 52.

The embodiment shown in Figure 9 is similar in many respects to that shown in Figure 4, and corresponding parts have therefore been given corresponding reference numerals. When the voltage generated by the generator 68 is higher than that supplied by the battery 58, the solenoid 70 will become energized, thereby drawing the arm 73 in contact with the core 72 of the solenoid, and also moving the contact point 64 into engagement with the fixed contact point 65 to close the circuit through the resistance coil 52. When the generated voltage drops, as when the engine is stopped, the spring 57 moves the arm 73 out of contact with the core 72 of the solenoid 70, and moves the contact point 64 away from the fixed contact 65 to break the heating circuit through the coil 52.

The invention thus comprehends a device in which an unbalanced choke valve is urged toward the closed position by a thermostat when cold, and heating means operate only when the engine has started running and the thermostat is exerting a force on the choke valve, to gradually decrease and finally to eliminate the force of the thermostat on the choke valve. The choke valve will then be moved to the full open position by the combined force of gravity acting on the unbalanced valve, and the force of the air entering the air inlet passage 10. As long as the engine continues to run, the choke valve will remain in the full open position. When the engine is stopped and cools off, the thermostat will uncoil until the hooked end of the thermostat engages the stop member 56, whereupon it will exert a force on the choke valve, urging it toward the closed position. No current will flow through the resistance coil 52, however, until the engine is started.

Although the invention has been described with particular reference to the embodiments shown in the drawings, it is to be understood that it may be embodied in other forms and is not limited except by the terms of the following claims.

I claim:

1. In a carburetor for an internal combustion engine having an electric ignition system including a generator to supply electric current, a main induction passage in the carburetor, an unbalanced choke valve pivotally mounted in

the induction passage, thermostatic means urging the choke valve closed when cold, and electric heating means adapted to heat the thermostat to decrease the force of said thermostat when the engine is started and electric current is supplied by the generator.

5 2. In a carburetor for an internal combustion engine having an ignition circuit, means for controlling the inflow of air to the carburetor, temperature responsive means for actuating said controlling means, and electric means in said ignition circuit operable only when the engine is operating for varying the force of said temperature responsive means.

3. In a carburetor having an air inlet passage, a choke valve controlling the flow of air into said passage, temperature responsive means controlling the choke valve when cold, electric means for controlling the action of the temperature responsive means, said electric means being operative only after the engine has been started, and means to interrupt the action of the electric means when the temperature responsive means ceases to control the choke valve.

25 4. In a carburetor having a main carbureting passage, an unbalanced choke valve, a throttle valve, a thermostat urging the choke valve closed when cold, and electric means operable to control the action of the thermostat only upon a substantial reduction in pressure in the main carbureting passage posterior to said throttle valve.

30 5. In a carburetor having a main carbureting passage, an unbalanced choke valve, a throttle valve, a thermostat urging the choke valve closed when cold, electric means operable to control the action of the thermostat only upon a substantial reduction in pressure in the main carbureting passage posterior to said throttle valve, and means to interrupt the action of the electric means when the thermostat ceases to urge the choke valve closed.

35 6. In a carburetor for an internal combustion engine having an electric ignition system, an ignition switch, an oil pump, an oil pressure actuated motor, an electric switch operable by said motor, a main induction passage in the carburetor, an unbalanced choke valve in the induction passage, temperature responsive means urging the choke valve closed when cold, and electric means to control the action of the temperature responsive means, said electric means becoming operable upon closing both the ignition switch and the oil pressure operated electric switch.

40 7. In a carburetor for an internal combustion engine having an electric ignition system, an ignition switch, an oil pump, an oil pressure actuated motor, an electric switch operable by said motor, a main induction passage in the carburetor, an unbalanced choke valve in the induction passage, temperature responsive means urging the choke valve closed when cold, electric means to modify the action of the temperature responsive means, said electric means becoming operable upon closing both the ignition switch and the oil pressure operated electric switch, and means to interrupt the action of the electric means when the temperature responsive means ceases to urge the choke valve closed.

45 8. In a carburetor for an internal combustion engine having an electric ignition system, an ignition switch, an intake manifold constituting a source of vacuum when the engine is running, an electric switch, a vacuum actuated motor adapted to close said switch when the

vacuum in the intake manifold reaches a predetermined value, a main carbureting passage, an unbalanced choke valve mounted in the carbureting passage, temperature responsive means urging the choke valve closed when cold, and electric means for supplying heat to the temperature responsive means, said last mentioned means becoming operable upon closing both the ignition switch and the vacuum motor actuated electric switch.

9. In a carburetor for an internal combustion engine having an electric ignition system, an ignition switch, an intake manifold constituting a source of vacuum when the engine is running, an electric switch, a vacuum actuated motor adapted to close said switch when the vacuum in the intake manifold reaches a predetermined value, a main carbureting passage, an unbalanced choke valve mounted in the carbureting passage, temperature responsive means urging the choke valve closed when cold, electric means to control the action of the temperature responsive means, said electric means becoming operable upon closing both the ignition switch and the vacuum motor actuated electric switch, and means to interrupt the action of the electric means when the temperature responsive means ceases to urge the choke valve closed.

10. In a carburetor for an internal combustion engine having an electric ignition system, an ignition switch, a generator, a generator operated electric switch, a main carbureting passage, an unbalanced choke valve mounted in the carbureting passage, temperature responsive means urging the choke valve closed when cold, and electric means to modify the action of the temperature responsive means, said electric means becoming operable upon closing both the ignition switch and the generator operated electric switch.

11. In a carburetor for an internal combustion engine having an electric ignition system, an ignition switch, a generator, a generator operated electric switch, a main carbureting passage, an unbalanced choke valve mounted in the carbureting passage, temperature responsive means urging the choke valve closed when cold, electric heating means controlling the action of the temperature responsive means, said heating means becoming operable upon closing both the ignition switch and generator operated electric switch, and means to interrupt the action of the heating means when the temperature responsive means ceases to urge the choke valve closed.

12. In a carburetor for an internal combustion engine having an electric ignition circuit, an ignition switch, an electric switch, means operative only during engine operation for closing said switch, a main induction passage in the carburetor, an unbalanced choke valve in the induction passage, temperature responsive means urging the choke valve closed when cold, electric means to modify the action of the temperature responsive means, said electric means becoming operable upon closing the ignition switch and the closing of the first mentioned switch.

13. In a carburetor for an internal combustion engine having an electric ignition circuit, an ignition switch, and an electric switch means operative only during engine operation for closing said switch, a main induction passage in the carburetor, an unbalanced choke valve in the induction passage, temperature responsive means urging the choke valve closed when cold, electric means to modify the action of the temperature

responsive means, said electric means becoming operable upon closing of both the ignition switch and the first mentioned switch, and means to interrupt the action of the electric means when the temperature responsive means ceases to urge the choke valve closed.

14. In a carburetor for an internal combustion engine having a source of pressure when the engine is running, an induction passage, a choke valve controlling the flow of air into the induction passage, thermostatic means controlling the choke valve, a casing surrounding the thermostat, electric heating means in the casing adapted to heat the thermostat under certain operating conditions, and switch means operable by said source of pressure to initiate a flow of electricity through the heating means when the engine is started.

15. In a carburetor for an internal combustion engine having an ignition circuit including a generator adapted to supply electric current, a main induction passage, an unbalanced choke valve adapted to control the flow of fluid into the induction passage, a thermostat adapted to urge the choke valve toward the closed position at low temperature, a casing surrounding the thermostat, an electric heating coil in the casing, a stop member in the casing adapted to receive one end of the thermostat, insulating means between the stop member and the thermostat, insulating means between the thermostat and the choke valve, and means including a switch adapted to initiate a flow of current to the heating coil when the engine has started and a predetermined flow of current is supplied by the generator.

16. In a carburetor for an internal combustion engine having an ignition circuit including a generator adapted to supply electric current, a main induction passage, an unbalanced choke valve adapted to control the flow of fluid into the induction passage, a thermostat adapted to urge the choke valve toward the closed position at low temperature, a casing surrounding the thermostat, an electric heating coil in the casing, a stop member in the casing adapted to receive one end of the thermostat, insulating means between the stop member and the thermostat, insulating means between the thermostat and the choke valve, and means including a switch adapted to initiate a flow of current to the heating coil when the engine has started and a predetermined flow of current is supplied by the generator, and means to interrupt the flow of current to the heating coil when the thermostat ceases to control the choke valve.

17. In a carburetor for an engine having means to supply pressure to a fluid when the engine is running, a main carbureting passage, an unbalanced choke valve adapted to control the supply of air admitted to the main carbureting passage, temperature responsive means controlling the choke valve and adapted to move the choke valve to the closed position at low temperatures, a casing surrounding the thermostat, electric heating means in the casing adapted to heat the thermostat, switch operating means adapted to supply electric current to the heating means upon the existence of a predetermined pressure in the pressure source, and insulating means to interrupt the flow of electric current to the heating means when the thermostat ceases to control the choke valve.

18. In a carburetor having an induction passage, a choke valve controlling the inflow of air to said passage, temperature responsive means influencing the movements of the choke valve,

and electric heating means for modifying the action of the temperature responsive means, said heating means becoming operative only when the engine is operating, and becoming inoperative when the temperature responsive means reaches a predetermined temperature.

19. A choke mechanism for the charge forming device of an internal combustion engine having in combination means for varying the fuel to air ratio in the mixture formed by said charge forming device comprising a choke valve for closing the air intake of said charge forming device, thermally responsive means for operating said valve, means other than the engine but rendered operative when the engine begins to run under its own power for heating the thermally responsive means, and means for rendering said last named means inoperative.

20. A choke mechanism for the charge forming device of an internal combustion engine having in combination means for varying the fuel to air ratio in the mixture formed by said charge forming device, thermally responsive means for operating said ratio varying means, means other than the engine but rendered operative when the engine begins to run under its own power for heating the thermally responsive means, and means operable by the thermally responsive

means for rendering the heating means inoperative.

21. A choke mechanism for the charge forming device of an internal combustion engine having in combination means for varying the fuel to air ratio in the mixture formed by said charge forming device, thermally responsive means for operating said ratio varying means, relatively remotely located with respect to the engine, heating means for raising the temperature adjacent the thermally responsive means more rapidly than the temperature adjacent the engine is raised and means operable by the thermally responsive means itself for rendering the heating means inoperative after a predetermined effect on said thermally responsive means.

22. A choke mechanism for the charge forming device of an internal combustion engine having in combination means for varying the fuel to air ratio in the mixture formed by said charge forming device, a thermostat for operating said ratio varying means, an electric heating device for heating the thermostat, a generator, means operable by the generator for causing said heating device to become operative, and means operable by the thermostat for rendering the heating device inoperative.

SCOTT F. HUNT.
